Silvers Patent Nov. 1. 1830. —

The subscriber referred to in these Letters Patent and working part of the same containing a description in the words of the said Silvers Patent his discovery of his improvements in the apparatus for boring earth for water.

No all in whom these parts shall come, I, Silvers, citizen of the City of New York and a citizen of the United States for Patent.

Do all know that I, Silvers, discover the inventor of a machine for boring the earth for water have invented constructed made and applied to use a new and useful apparatus which is intended principally for boring into the earth the specification of the pipes and tools to use, as follows:

No 1. The pipe for sinking in the earth is of cast iron, of an equal bore throughout, but of diminished thickness taken from the outside near the end till it is small enough to fit into the socket formed in the next length of pipe; the socket is formed by a band of wrought iron, placed on the end of the pipe, but which when cold contracts and so remains permanent; the next length of pipe is formed in the same manner and so may be continued to any required length or depth; the joints are closed and sealed by driving wedges, and so resist either water or steam.

No 2. The pipe is cylindrical for boring the earth, so as to pass through the pipe. It is made of iron pointed with steel; there is a spring on the outside when most enlarged it is larger than the outside of the pipe to the end that when it gets below the pipe it may cause a hole to be bored larger than the pipe to be received, and a kick is effected by the distinction caused by the spring.

No 3. The chain and levers for forcing down the pipe. The levers are two pieces of iron made fast to the platform by pins,快钉, or other convenient means; the chains have hooks on either end. One hook fastens on the socket; the other is passed with the chain round the lever and hook as in such part of the chain as the pinches it may

square at pleasure. No. 4. Rods connected by Cratch joints and screws. The rods are square lengths of iron. There is a square cratch formed at each end of the length into which one admits the other. The ends are held by screws which pass each other transversely by this means any length of rods may be securely connected, gaining the best both of flexibility and strength.

No. 5. The Spring Chisel is formed by a spring which confines the operation of the chisel or punch to the edge of the pipe as in the drawing. its use is for breaking off pieces of stone which in part obstruct the passage of the pipe.

No. 6. The rock boring tools are:- First a set of chisel or punches described in the drawing. Second a reaming bit. It is formed of four dies of steel well bolted on a square rod, which extends below as a guide. its use is to enlarge a hole already made to any proposed size:- the whole of the above tools and apparatus are used with the machine always patented to said Genl. Dibron dated twenty fourth of March one thousand and eight hundred and twenty five, as will appear on reference to the drawing annexed.

* In testimony that the above is a true specific
ation of my said invention I have here set my hand and seal this
thirtieth day of September in the Year of our Lord one thousand eight
hundred and thirty
